COMBINED DRILL BIT HOLDER AND HOLE SIZE INDICATOR

Joel A. Howard, Fort Lee, N.J., assignor to Howard
Hardware Products, Inc., Bloomfield, N.J.

Filed Jan. 14, 1974, Ser. No. 433,199

Term of patent 14 years

Int. Cl. D3—02

U.S. Cl. D87—1 R

FIG. 1

FIG. 2

FIG. 3

FIG. 4

FIG. 5

FIG. 6

FIG. 7

FIG. 1 is a top plan view of a combined drill bit holder and hole size indicator, showing my new design;

FIG. 2 is a front elevational view thereof, the rear being the mirror image thereto;

FIG. 3 is a left side elevational view thereof;

FIG. 4 is a right side elevational view thereof;

FIG. 5 is a bottom plan view thereof;

FIG. 6 is a cross-sectional view of FIG. 1 as taken from line 6-6; and

FIG. 7 is a cross-sectional view of FIG. 1 as taken from line 7-7.

I claim:

The ornamental design for a combined drill bit holder and hole size indicator, substantially as shown and described.
